APPARATUS FOR STRINGING TOBACCO LEAVES

Rush D. Touton, Wynnewood, Pa.

Application April 12, 1951, Serial No. 220,618

2 Claims. (Cl. 214—5.5)

1

This invention relates to stringing tobacco leaves.

As is well known, when tobacco is harvested, the leaves are strung on lengths of string secured at one end to a lath, the free end of the string, after the leaves are strung thereon, is attached to the other end of the lath and the whole then racked up in a curing barn with the leaves hanging from the string for the curing of the tobacco leaves.

When the tobacco has cured, the laths are taken down, the ends of the string are cut free from the lath, the tobacco leaves pushed together and the balance of the string may be wound about the butt portions of the leaves and secured to form hands.

In practice heretofore, the stringing of the tobacco leaves has been accomplished manually by operators who string them by passing a needle, carried by the string at its free end, through the butts of the leaves. This operation is open to a number of objections, chief among which is variation in the number of pairs of leaves per lath, unequal spacing of the pairs on the string, wide variation in the number of laths strung per day by different operators, which results in a limited average production, breakage of leaves due to inept operators, loss from falling leaves during curing resulting from improper stringing, difficulty in obtaining requisite labor for a short seasonable occupation, and rising labor costs coupled with decreasing productivity.

As a consequence, there have heretofore been many efforts made to provide mechanism and procedure for the mechanical stringing of tobacco leaves which would give a constant number of pairs of leaves per lath, equal spacing of the pairs on the string and increased productivity per operator.

Generally speaking, the apparatus disclosed herein provides economical and uniform spacing of a consistent number of leaves per lath, the leaves being securely held by a pair of strings with a minimum of falling leaves. The apparatus provides for securing leaves of tobacco at spaced intervals between the strings, which are secured together and to one end of a lath, by successively crossing the strings over and under one another, or crossing one string about the other, between tobacco leaves, the butts of which are successively presented between the strings. More particularly, the strings are so arranged and manipulated that portions thereof will extend at rest for a period between crossings to enable successive tobacco leaves to be presented between them.

2

The stringing operations are generally carried out in the barns or drying sheds in which the tobacco is to be stored. It is desirable, therefore, that the stringing apparatus occupy a minimum of floor space to allow maximum space for the traffic of handling the tobacco both before and after it is strung.

It is an object of the present invention to provide simple apparatus for indicating to the operator the proper spacing between the tobacco leaves which are to be successively inserted between the strings.

It is a further object of this invention to provide simple apparatus including means which function as guides for indicating to the operator the proper spacing between the tobacco stems which are successively inserted between the strings and also the degree or depth of insertion of the tobacco stems as they are successively inserted between the strings.

These and other objects of the invention will become apparent from the following description when read in conjunction with the accompanying drawings, in which:

Figure 1 is a front elevation of apparatus embodying the present invention;

Figure 2 is a top view of the apparatus shown in Figure 1;

Figure 3 is a view taken on the trace 3—3 of Figure 2;

Figure 4 is a view taken on the trace 4—4 of Figure 2; and

Figure 5 is a fragmentary showing of a portion of the apparatus shown in Figure 1.

Referring to the figures, the apparatus includes the framework 2. The horizontal shafts 4 and 6 are mounted in the framework by means of suitable bearings 8. The shaft 4 extends outwardly of the right hand side framework 2 as viewed in Figure 1 and has mounted on the outer end thereof a sprocket 14. The driving motor 12 drives the sprocket 14 by means of the drive chain and the sprocket 14.

The lath drive roller 5 is mounted on and driven by the shaft 4. The drive roller 5 is made of, or surfaced with, rubber or other suitable material providing a high degree of friction on engagement with a lath. The member 3 is attached to the framework and provides a smooth backing member for the lath to slide against as it is driven by the roller 5.

Also mounted on and driven by the horizontal shaft 4 is the bevel gear 16 which is in engagement with the bevel gear 18 and thus drives the vertical shaft 20 which is mounted in the frame-

work 2 by means of suitable bearings 21. Attached to the upper end of the shaft 20 is the eccentrically mounted driving pin 22 which, acting through the drive link 24, moves the vertical shaft 26 in a rotary direction by its action upon the eccentrically mounted pin 27 within the slot 25.

Vertical shaft 26 is rotatably mounted in bearings 28 which are supported by the framework 2. Attached to and rotatable with the shaft 26 are the mounting rods 32 which mount and support spools of string 34 and 35, the ends of the rods 32 being provided with the hinged lock member 36 for retaining the spools on the rods when the rods rotate with the shaft 26.

Mounted on the lower end of the rotatable shaft 26 is the string tensioning apparatus indicated generally by the arrow 38. As shown in greater detail in Figure 5, this apparatus includes the member 40 which is rigidly attached to the shaft 26 and rotatable therewith and the member 42 which is freely mounted on the shaft 26 and held thereon in pivotal relation therewith by means of the pin 44. Attached to the member 40 are the spring retainer cups 46 and 48. The pairs of cups 50 and 52, and 54 and 56 are supported by and freely movable on the studs 58 and 60, respectively, which are rigidly mounted in the member 42. The cups 46 and 50 retain the spring member 62 and the cups 48 and 54 retain the spring member 64. It will be apparent that the member 42 is held against the pin 44 by the action of the springs 62 and 64, and the force exerted between the cups 50 and 52, and between the cups 54 and 56 will be substantially balanced due to the pivotal mounting of the member 42 against the pin 44.

Mounted on the outer portions of the member 42 are string guides 66, 68, 70 and 72. The string leaving the spool 35 passes through the string guide 68, around the pin 58, between the cups 50 and 52, through the string guide 66 and downwardly, as indicated at 75. The string leaving the spool 42 passes through the string guide 72, between the cups 54 and 56, through the string guide 70 and downwardly, as indicated at 74. Lower ends of the strings 74 and 75 are secured generally by tying to the lower end of a lath 76.

Also attached to the vertical shaft 26 and on a radial plane with respect thereto are the plates 78 and 80. Mounted between these plates on pins 82 and 84 are the rollers 86 and 88. Pivottally mounted on the framework 2 by means of the hinge assembly 90 is the leaf 92. Leaf 92 is so positioned as to engage the two rollers 86 and 88. The outer end of the leaf 92 is attached to the rod 94 which passes into the cylinder 96 and has attached to the end thereof within the cylinder a piston which, acting within the cylinder, tends to restrain the rate of motion of the leaf 92. The spring 95 acting between the leaf 92 and the member 93 attached to the framework 2 urges the leaf inwardly against the rollers 86 and 88. The leaf 92 is actuated by rotation of the shaft 26 and the rollers 86 and 88, and by the spring 95 is will be hereafter described.

The horizontal shaft 6 is driven from the horizontal shaft 4 by means of the spur gears 98. Rigidly mounted on the shaft 6 is the member 100 having four radially extending blades 102.

In operation of the apparatus, an operator will stand before the machine facing the apparatus, as viewed in Figure 1. The operator will place a lath 76 in position back of the lath drive roller 5 and secure to the lower end thereof the ends

of the strings 74 and 75 with the strings being in a position passing in front of and partially around the member 100. The operator then starts the drive motor 12. Operation of the drive motor will drive the horizontal shaft 4, rotating the lath drive roller 5 and causing the lath 76 to move downwardly.

Operation of the motor 12 will cause the shafts 4 and 20 to rotate, and the eccentrically mounted drive pin 22 will cause the member 24 to drive the eccentrically mounted pin 27 and rotate the shaft 26. It will be apparent, however, that, as the shaft 26 is rotated, one of the rollers 86 and 88 will pass under the leaf 92 bearing against the leaf and moving the leaf away from the shaft 26 against the urging of spring 95 as the roller moves into the position between the spring leaf and the shaft. As soon as the roller passes beyond an intermediate position between the spring and the shaft, the force of the spring 95 acting through the leaf 92 and against the roller will cause the shaft 26 to rotate more rapidly than the rate at which it is being driven by the action of the member 24. The slot 25 in the member 24 permits an overrunning motion of the pin 27 of the shaft 26 whereupon the shaft comes to rest when the two rollers 86 and 88 are again both in engagement with the leaf 92.

The shaft remains in this position until, as a result of continued rotation of the shaft 20 and the drive pin 22, the eccentric pin 27 is engaged by one end of the slot 25 and the shaft 26 then driven for another quarter of a revolution by the action of the member 24 against the pin 27. Thus the combined action of the slotted member 24 and the rollers, leaf and spring assembly is that the shaft 26 is driven at a relatively slow rate of speed for a quarter of a revolution by the member 24 and then driven for the next quarter of a revolution at a relatively high rate of speed by the action of the spring 92 against one or the other of the rollers 86 and 88. This rapid motion is followed by a period of rest during which time the member 24 is moved until the pin 27 is engaged by one end or the other of the slot 25 in the member 24 whereupon the shaft 26 is again rotated for a quarter of a revolution by the action of the rod 24.

The result of this intermittent rotation of the shaft 26 is to cause intermittent rotation of the string tension balancing apparatus 38 and of the strings 74 and 75 passing therethrough.

The lower ends of the strings 74 and 75 are, as has been previously described, tied to the lower end of the lath, and the lath, which is being driven downwardly by the drive roller 5, draws string from the spools 34 and 35 through the tension balancing apparatus 38. The member 100 is positioned on a shaft 6 in such a manner that, immediately after the shaft 26 has come to rest with the strings substantially in a position as shown in Figure 1, the radial blades 102 provide guide means for the operator in placing a tobacco leaf stem between the strings, the leaf being laid upon the horizontal blade and butted against the vertical blade.

It should be noted that the angle between the strings 74 and 75 is such that, as the tobacco stem is inserted in the apex of the angle between the strings, the strings cut into the tobacco stem forming grooves therein which serve to hold the stem between the strings after being placed therein and before the strings are rotated to insure permanent retention of the tobacco stem between the twisted strings, and to cut the outer

fibers of the tobacco stem thereby promoting drying of the tobacco stem.

As the machine operates, the operator will place a leaf or a plurality of leaves against each blade 102 of the member 100 as the member rotates. The rotation of the blades 102 provides spacing and timing guides for the operator whereby the operator, being guided thereby, will insert tobacco leaves between the strings at the proper time intervals and at the proper space intervals, as well as with uniform extension of the butts of the successive tobacco stems above or beyond the strings.

After the proper number of tobacco leaves have been inserted between the strings as required to string a lath, the lath will be driven out of the friction drive roller and will be thereby automatically released therefrom. The leading end of the lath will come to rest upon the floor or on any suitably positioned catching means to hold the lath at rest while the operator grasps the lath at its upper end, cuts the strings 74 and 75, draws the strings tight and secures the strings supporting the tobacco leaves to the upper end of the lath. The vertical stringing of the leaves to a lath permits the use of less string tension to properly retain the strings during stringing than is required if the lath is extended horizontally during stringing. Since the leaves in the vertical stringing arrangement are substantially stacked one upon the other, they tend to support one another until the strings are finally secured to the upper end of the lath. The indentations in the stems are not fully formed until the strings are drawn tight and secured to the lath. This minimum tension requirement of the strings is an advantage when certain smaller types of tobacco leaves are strung.

After placing the strung lath on a suitable rack, the operator will position another lath behind the driving roller, secure the cut ends of the strings 74 and 75 to the lower end of the lath, start the machine and proceed to feed leaves between the strings which are drawn over the member 100 as the lath is driven downwardly.

This apparatus not only operates over a minimum of floor space, but has the further advantage of providing a comfortable working position for the operator. The operator is required only to select a leaf of tobacco and carry it forward into the presented space provided by the rotating spacer member over which the strings are drawn while being intermittently twisted. If it is desired to place two leaves of tobacco between the strings in each position of the rotating spacer member, the operator will grasp a leaf in each hand and simultaneously carry the leaves forward into the spacer member.

While the invention disclosed herein is described as being a vertically operating machine, i. e., a machine in which the lath lies in a vertical position, it will be apparent that the machine may be rotated 90° and the lath be carried horizontally by the addition of a suitable guide means to support the outer end of the lath. While the horizontal operation of the machine abandons the beneficial feature of minimum re-

quired floor space, and must be operated with greater string tension, the various other features of the machine may be employed equally well in a horizontally positioned machine as in a vertically positioned machine.

It will be apparent that these and other modifications may be made in the embodiment of the invention disclosed herein without departing from the scope of the invention as set forth in the following claims.

What is claimed is:

1. Apparatus for stringing tobacco leaves on a lath comprising means for supporting a pair of lengths of string, intermittently rotating means for intermittently rotating and feeding spaced strings from said supporting means, means for driving the lath in a direction away from said intermittently rotating string feeding means, the ends of the strings being secured to the leading end of the lath and the strings being drawn through said string feeding means by the travel of the lath, and rotating guide means over which the strings pass while being drawn from said string feeding means by the moving lath, said rotating guide means comprising a member having radially extending blades, the speed of rotation of the guide means being such that the rotating blades provide guides for insertion by an operator of successive tobacco stems between the spaced strings between successive rotations of the strings by the intermittently rotating means.

2. Apparatus for stringing tobacco leaves on a lath comprising means for supporting a pair of lengths of string, intermittently rotating means for intermittently rotating and feeding spaced strings from said supporting means, means for driving the lath in a direction away from said intermittently rotating string feeding means, the ends of the strings being secured to the leading end of the lath and the strings being drawn through said string feeding means by the travel of the lath, and rotating guide means over which the strings pass while being drawn from said string feeding means by the moving lath, said rotating guide means comprising a member having four radially extending blades, said blades providing guides for insertion by an operator of successive tobacco stems between the spaced strings between successive rotations of the strings by the intermittently rotating means, said blades providing guides to both the spacing between successive tobacco stems and the degree of insertion of the successive tobacco stems between the strings.
